UNITED STATES PATENT OFFICE.

GEORGE E. PICKUP, OF NEWARK, OHIO, ASSIGNOR TO THE WEHRLE COMPANY, OF NEWARK, OHIO, A CORPORATION OF OHIO.

DESIGN FOR A STOVE.

No. 39,381.

Specification for Design.

Patented June 2, 1908.

Application filed April 3, 1908. Serial No. 425,066. Term of patent 7 years.

To all whom it may concern:

Be it known that I, GEORGE E. PICKUP, a citizen of the United States, residing at Newark, county of Licking, and State of Ohio, have invented a new, original, and ornamental Design for Stoves, of which the following is a specification, reference being had to the accompanying drawing, forming part thereof.

My invention is shown in the accompany-

ing drawing in which the device is shown by a single figure in perspective illustrating the design of my invention.

I claim:

The ornamental design for a stove, as shown.

G. E. PICKUP.
